DEVICE FOR FACILITATING THE AXIAL ADJUSTMENT OF ROLLERS ON PRINTING PRESSES

William E. Featherly, Athens, N. Y., assignor of one-half to John Burgio, New York, N. Y.

Substituted for abandoned application Serial No. 170,072, June 24, 1950. This application April 23, 1957, Serial No. 654,611

2 Claims. (Cl. 340—282)

The present invention relates to improvements in accessories to rotary printing presses of the type which employs revolving cylinders or longitudinal rollers for both the printing form and the impressional surface. More specifically, the invention relates to a new and improved device for facilitating the axial adjustment of rollers on printing presses. This application is a substitute of my abandoned patent application Serial No. 170,072, filed June 24, 1950.

Rotary presses are provided with pairs of parallel, co-operating rollers, one of which is a metal cylinder and the other of which is a so-called "composition roller" of rubber or of any other suitable insulating material. The radial distance between both cylinders has to be adjusted frequently, and it is important that this adjusting or setting is made accurately. Hitherto for this purpose a sheet of paper has been inserted between rollers, and it required considerable skill and much time to set the rollers properly.

One object of the present invention is the provision of a device of the character described which will permit a more accurate and speedier adjustment of the rollers, than was possible hitherto, and which does not require any considerable amount of skill for a perfect and fast setting or adjustment.

Another object of the present invention is the provision of a device of the character described which is safe in operation and inexpensive to manufacture, so that it can be sold at a very reasonable price and can be used widely wherever rotary presses are in operation.

With the foregoing and other objects in view which will appear as the description proceeds, the invention consists of certain novel details of construction and combinations of parts hereinafter more fully described and pointed out in the claims, it being understood that changes may be made in the construction and arrangements of parts without departing from the spirit of the invention as claimed.

In the accompanying drawing a preferred form of the invention has been shown.

In said drawing:

Figure 1 is a fractional side elevational view, partially in the form of a wiring diagram, of a preferred embodiment of my invention; and

Figure 2 is a cross-sectional fractional view on the line 2—2 of Figure 1.

Similar reference characters refer to similar parts throughout the several views.

In the drawing the numeral 2 denotes a metal cylinder or a conductive roller of a rotary press which is parallel to and cooperates with a composition roller 4 of rubber or of any other suitable soft, insulating material. Other parts of the press are not shown. The numeral 6 denotes conductive bands of thin sheet metal whose main portions are circular and adapted for encompassing annular, spaced portions of the roller 4 and whose end portions are parallel to each other and bent outwardly from said main

2

portions, so as to form clip-shaped sleeve members. A screw 8 is extended through the extremities of each member 6 and connects thereto one end of a wire 10. Another wire 12, is connected to one terminal of each of a plurality of electrical signal lamps 14, while the second terminal of each lamp 14 is connected to the other end of each wire 10.

A wire 16 is connected with one end to the conductive roller 2, and with its other end to one terminal of the low-voltage coil of a transformer 18. The high-voltage coil of the transformer 18 is connected to a source of current (not shown) by means of a pair of wires 20.

In order to adjust a pair of rollers, the screws 8 are removed from the bands 6 and the latter are laid tightly around the roller 4 in spaced relation to each other. Then the end of each band 6 are connected to each other and to a wire 10 by means of the screws 8, the wire 16 is connected to the roller 2 or is grounded, and the transformer 18 is energized. Then the rollers are moved more or less closely toward each other until all the lamps 14 light up. Thereafter the rollers are turned a fraction of a revolution. If all the lamps 14 remain lit up during about one quarter of a revolution of the rollers, the setting is completed, and the bands 6 can be removed from the roller 4.

The removing of the bands 6 is done after removing therefrom the screws 8 and bending straight each band 6 at one end, so that each band can be pulled out from between the rollers 2 and 4 without increasing the spacing between the rollers 2 and 4. The transformer 18 reduces the voltage on the bands 6 to about six to twelve volts, so that the device will be safe and the operator cannot get any electric shocks while he is manipulating the device. The lamps 14 are provided with low-voltage light bulbs.

Since certain changes may be made in the above article and different embodiments of the invention could be made without departing from the scope thereof, it is intended that all matter contained in the above description or shown in the accompanying drawing shall be interpreted as illustrative and not in a limiting sense.

It is also to be understood that the following claims are intended to cover all of the generic and specific features of the invention herein described, and all statements of the scope of the invention which as a matter of language might be said to fall therebetween.

Having thus fully described my said invention, what I claim as new and desire to secure by Letters Patent in the United States is:

1. A device for facilitating the axial adjustment of rollers on printing presses comprising a plurality of conductive sleeves adapted for being placed detachably in spaced relation from one another around annular portions of a composition roller of a printing press, a

plurality of signal lamps each of which having its first terminal connected to one of said sleeves, and a transformer having two coils one of which is connected to a source of current while the other coil has one of its terminals connected to all the second terminals of said lamps and has its other terminal connected to a conductive roller which cooperates with said composition roller.

2. A device of the character described comprising a plurality of thin conductive bands whose main portions are circular and adapted for encompassing annular portions of a non-conductive roller of a printing press and whose end portions are parallel to each other and bent outwardly from said main portions, a screw being extended through said end portions of each band, a plurality of electric signal lamps each of which has its first terminal connected to an end portion of one of said bands by means of one of said screws, and a transformer having

two coils one of which is connected to a source of current while the other coil has one of its terminals connected to all the second terminals of said lamps and has its other terminal connected to a conductive roller which is parallel to and cooperates with said non-conductive roller. 5
